(57) **CLAIM**

The ornamental design for an electrical connector housing, as shown and described.

DESCRIPTION

FIG. 1 is a front, top and right side perspective view of an electrical connector housing showing my new design; FIG. 2 is a rear, bottom and left side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof;

FIG. 8 is a left side view thereof;

FIG. 9 is a cross-sectional view taken along line 9-9 in FIG. 3;

FIG. 10 is a cross-sectional view taken along line 10-10 in FIG. 3;

FIG. 11 is a cross-sectional view taken along line 11-11 in FIG. 3; and,

FIG. 12 is a cross-sectional view taken along line 12-12 in FIG. 3.

The broken lines illustrate portions of the electrical connector housing that form no part of the claimed design.

1 Claim, 12 Drawing Sheets
